UNITED STATES PATENT OFFICE.

WALTER S. DAVIS, OF CONTOOCOOK, NEW HAMPSHIRE.

PAPER-BOX MACHINE.

SPECIFICATION forming part of Letters Patent No. 352,304, dated November 9, 1886.

Application filed November 12, 1885. Serial No. 182,513. (No model.)

To all whom it may concern:

Be it known that I, WALTER S. DAVIS, a citizen of the United States, residing at Con-
5 tocook, in the county of Merrimack and State
of New Hampshire, have invented certain new
and useful Improvements in Paper-Box Ma-
chines, of which the following is a specifica-
tion.

My invention relates to machines for mak-
10 ing paper boxes of various dimensions, the ob-
ject of my invention being to provide in a ma-
chine mechanism by which boxes may be
formed (excepting the cover) entire from three
15 pieces of card or straw board, which are pre-
viously cut the proper dimensions to form a
box of a given size and placed in their re-
spective receptacles, from which they may be
delivered formed into boxes, pasted together,
20 and carried singly from the machine by the
said mechanism with great rapidity.

My invention consists in the combination
25 of the various mechanisms necessary for car-
rying the different parts from which a box is
to be formed to their proper place, forming and
pasting the said parts together and depositing
30 the completed box upon a suitable carrier or
carriage, by which said box may be removed
from the machine, all of which will be clearly
described in the following specification, and
illustrated in the accompanying drawings,
35 forming part thereof.

Figure 1 represents an end elevation of my
improved machine, Fig. 2 being the rear side
elevation. Fig. 3 is a vertical section taken
35 centrally from front to back of the machine,
and showing one of the card board receivers
partially filled, with those parts which form
the body of a box and the reciprocal and
rotative mechanism. The parts are carried
40 singly from said receiver to their proper po-
sition under the plunger or former. Fig. 4 is
an end sectional elevation, which better illus-
trates the actuating mechanism applied to
those three feed-rolls which are shown in Fig.
45 3 as mounted upon the end frames, and their
rigid connections. Fig. 5 is a sectional plan
view of a portion of the frame of the machine,
the adjustable tables between which a box is
50 formed, the screw-rods and gearing by which
said tables are operated, and the feed-rolls
which were shown in Fig. 4. Figs. 6 and 7

are respectively a side elevation and plan
view of the sliding blocks, adapted to move in
grooves formed in the adjustable tables, and
to carry the adjustable stops provided thereon 55
for preventing those parts which form the
body of a box from moving beyond the re-
quired limit under the former. Fig. 8 is a
plan view of a cross-frame which carries an
adjustable bed-table, an adjustable table upon 60
which the receivers for those parts composing
the ends of a box are secured, and a slide for
carrying said parts to their destination, ready
to be pasted to the body of a box. Fig. 9 is a
cross-section of all above line Y Y, Fig. 8. 65
Fig. 10 is a sectional view showing the former
in a position to form a box, one of the paste-
rolls in readiness to apply paste as it passes
down, the card-boards which are to form the
70 ends of a box in their proper position relative
to the said former, and also the adjustable bed-
table. Fig. 11 is an enlarged sectional view
showing the paste boxes and rolls in end eleva-
tion and the mechanism by which they are 75
drawn toward a box in order to place a layer
of paste thereon. Fig. 12 is a cross-section
of one of the paste-boxes, showing the man-
ner of mounting the roll therein. Fig. 13 is
a plan view of the sliding bed-table. Fig.
14 is a plan view of a slide which forms an 80
important part of the mechanism for deposi-
ting the ends of a box in their proper posi-
tion. Fig. 15 is a longitudinal sectional ele-
vation of the frame shown in plan, Fig. 8
having the parts shown in Figs. 13 and 14 in 85
their respective positions and also in section.
Fig. 16 is a cross-section of one of the adjust-
able tables having the stop, against which the
heads or ends of a box are thrust, hinged
thereto. Fig. 17 is an elevation showing both 90
chutes from which the ends of a box are fed
out, Fig. 18 being a plan view of same. Fig.
19 is a general plan of the table upon which the
aforesaid chutes are adjustably secured. Fig.
20 represents an edge view of the same. Fig. 21 95
is a sectional elevation showing the manner of
securing the chutes upon the table seen in Fig.
20. Fig. 22 is an elevation of one of the chutes
having in its proper position the slide by which
the ends of a box are delivered singly there- 100
from. Fig. 23 is a plan view of the same,
showing the slide in the act of delivering an

end of a box. Fig. 24 is an enlarged elevation of one of the pressure-plates by which the ends of a box are stuck to the body thereof, connected to a section of the lever by which it is operated. Fig. 25 is a section of one of said levers, having connected to its lower end the actuating mechanism, consisting of a cam and horizontal levers. Fig. 26 is a plan view of a portion of the actuating mechanism for said vertical levers, showing sections of that portion of the frame of the machine upon which said mechanism is mounted. Fig. 27 is an enlarged elevation of one of the bevel-gears and pinion by which the vertical shafts driving the parts shown in Figs. 13 and 14 are operated. Figs. 28 and 29 are respectively an elevation and plan view of either of the slotted arms which are mounted upon the top of said vertical shafts, and which are connected by suitable sliding blocks to the slots shown in the said parts Figs. 13 and 14. Fig. 30 illustrates one manner of constructing an adjustable former. (Shown in elevation.) Fig. 31 is a plan view of same. Fig. 32 is a perspective view of a partly-completed box.

Like reference-letters indicate corresponding parts throughout the various views.

The frame may be of any convenient design, and consists of suitable uprights, A A', and various connecting parts, to be mentioned as opportunity offers in the following description. The pieces of card-board which form the bottom and sides of a box, after being cut to certain dimensions, are first placed in the receptacle B, which is located at the back of the machine, from which they are fed out through slot b at the bottom of the pile, singly, toward and between the feed-rolls C C', the mechanism by which this movement is obtained consisting of a serrated rack or frame, B', and suitable means by which it may have a reciprocating motion to and away from the feed-rolls C C', a convenient method for accomplishing this being shown best in Fig. 3 of the accompanying drawings, in which b' is a block connected at its top to a portion of the frame B', its bottom being swiveled to a slide, D, the outer end of which is connected by swivel to a lever, E, fulcrumed about midway from either end thereof to the under side of one of the parts a of the frame, as at E'. In order to transmit a rocking motion to the opposite end of said lever, said end is slotted lengthwise, said slot being long enough to afford sufficient play to a bolt, e, or other suitable connection, which passes through the slotted end of said lever, and the free end of an arm, F, which is revolved horizontally by a system of bevel-gearing and shafts connecting with the counter-shaft G. If desired, the arm F may be constructed with a slot for rendering its connection with the lever E adjustable, and thus giving a varied stroke to the feeding serrated frame B'. This receptacle B may be made in some approved adjustable form relative to its width and length, in order that it may readily ac-

commodate itself to the various dimensions of card-board required for different sizes of boxes; or different-sized receptacles B may be provided for use, as required. The feed-rolls C C' are mounted in bearings formed in either of the upright frames A A', suitable springs, c c', exerting a pressure upon the journals of the roll C' toward the roll C. These are connected by spur-gears H H' at one end, the roll C being provided outside of the spur-gear H with a bevel-pinion, I, meshing with the bevel gear J, mounted on upper end of vertical shaft J', hung in suitable bearings and connected at its lower terminus with the driving-shaft K by bevel gears j j', by which said feed-rolls receive their motion. When these pieces of card-board which form the bottom and sides of a box shall have passed the feed-rolls C C', they enter between trucks L L', which carry them as far as the adjustable stop-pieces M, secured to the adjustable forming-tables N. The trucks L are one-half inch (more or less) in thickness and three inches (more or less) in diameter, and are mounted upon one end of either shaft l in suitable bearings, one of which is formed upon the under side of said tables N, and the other of which is provided upon either of the parts a' of the frame, said trucks L projecting through slots n in either of the tables N, so that their periphery shall be one-quarter inch (more or less) above the upper surface of the said tables, as seen in the drawings.

The outer ends of either of the shafts l are provided with belt-pulleys l', which are connected by belts with the pulleys c', mounted near either end of the feed-roll C, as seen in full lines, Figs. 1 and 2, and dotted lines, Fig. 3, by which motion is communicated to the trucks L. The upper trucks, L', act merely as pressure-rolls to keep the card-board in contact with the trucks L, and they are designed to drop directly over the said trucks L, in order that their work may be the most effective. The last-named rolls must of necessity move with the adjustable forming-tables, which is provided for by splining the pulleys l' to the shafts l, so as to admit of the necessary adjustment longitudinally of said shafts l. Some provision must be made for a like adjustment of the trucks L', which will be hereinafter explained.

The tables N rest upon the parts a of the frame, and in order that they may be adjusted relative to the width of box required to be made, between which tables said box must pass downward while being formed, said tables are made somewhat longer than the distance from either outside edge of the parts a, and upon the under side of these projecting ends are formed lugs n', to which are threaded the screw-rods O, mounted in bearings O' near either end thereof and secured to the outside edge of either of the uprights A A', one of said rods with its bearings being shown in Fig. 2. The lugs n' on one of the tables N will be tapped

with a right thread, and those upon the other table with a left thread, and the threads on the rods O will be cut accordingly, so that by rotating said rods both simultaneously in one direction the said tables may be moved apart, and when rotated in the opposite direction they will be drawn toward each other. This is accomplished by a light horizontal shaft, P, mounted in bearings P', secured to the outside 10 of the upright A, and provided with worm-gears p, meshing with spur gears o, mounted on one end of either of the screw-rods O, as shown best in Fig. 1. Said shaft P is also provided upon one end with a suitable crank, p', by which it may be operated. When the said pieces of card-board which form the bottom and sides of a box shall have been deposited upon the forming-tables N in their proper position, they must be forced down between said 15 tables by a suitable die or former in order to bend up the sides thereof. This may consist of a rectangular wooden block or hollow iron or metal box, Q, of the proper dimensions, as seen best in Fig. 3; but in order to avoid the necessity of providing a separate plunger or former for the various sizes of boxes capable of being made by this machine I prefer the construction illustrated by Figs. 30 and 31 of the drawings, in which the parts q q' form a 20 cylindrical hub, the contacting surfaces of either of the parts q q' being grooved for the reception, respectively, of the adjustable slides q' q'', which are placed as seen in Fig. 31, the slides q'' being above and resting upon the tops 25 of the slides q'. On the outer ends of either of the slides q'' are hinged suitable right-angle pieces, q^t, their heights corresponding to that of the deepest box the machine is capable of making. The lower slides, q^s, are provided in 30 like manner on either outer end with right-angle pieces q^s. Thus to adjust said right-angle pieces q' q^s to any given size of box the operator has simply to move them to or away from the parts q q' and rotate the latter in opposite 35 directions, when the bolts q⁶, which pass through the parts q q', may be tightened, the right-angle pieces q' q^s set, so that either their sides or ends respectively may be parallel, and the adjustable die or former will be ready for 40 use.

The part q is mounted upon the lower end of a square or rectangular bar, R, for which bearings are formed in the cross-frame a², secured between the uprights A A'. The upper 45 end of the bar R enters and is secured to a cross-bar, R', by rivets or bolts r, and the necessary vertical movement required by the die or former Q is communicated to the cross-bar R' by the vertical bars S, located outside of either of 50 the uprights A A', the upper ends of which are pivoted to the ends of said bar R', their lower ends being connected to the bar S', pivoted to the uprights A A', for the purpose of maintaining the bars S as nearly as possible in 55 a vertical position while moving up and down, the pivot s, connecting said bars S S', project-

ing far enough on the outside of the same to carry the friction-rolls s', which enter cam-grooves t, formed in the gear-wheels T, mounted upon either end of the counter-shaft G and 70 meshing with the pinions k, mounted upon the driving-shaft K.

The cross-frame a² is adapted to carry suitable sliding frames, U, fitted to ways formed thereon. Horizontal adjustable shafts u, carrying the pressure-trucks L', are fitted in the lower end of said frames U, and by means of a set-screw, u', threaded to said frames and acting upon said shafts u, the operator is enabled to adjust the trucks L' relative to the trucks 80 L, as previously mentioned. As the pieces of card-board upon which these trucks L' L' operate must be bent in order to form the sides and bottom of a box, it becomes necessary that the upper trucks, L', must be raised out of the way 85 before the die or former Q operates upon said card-board.

Before describing the mechanism by which the said rolls are raised it may be well to here state that the peculiar form of the cam-grooves 90 t in the gear-wheels T which in practice I find most preferable is such that while the said wheels T are making one quarter-revolution the die or former Q is detained at its highest elevation, the next quarter-revolution bringing said die or former thence downward to its lowest limit of movement, the next or third quarter-revolution detaining the said die in the last-named position, while the fourth quarter-revolution carries the said die back to the 100 first-named position, or its highest limit of motion.

The mechanism by which the frames U, carrying the trucks L', are operated is dependent for its motion upon that of the bar R, carrying 105 the die Q, and consists of the following parts: A horizontal shaft, V, having bearings V' secured upon one side of the cross-frame a², is provided at either end with arms v, which pass thence through vertical slots or openings u², 110 formed in the sliding frames U, and connect at their free ends with the bars W, the other ends of said bars being pivoted, as at u², to the said frames U, and midway from either end thereof with a short arm, v', adapted to be 115 acted upon by the vertical bar r', bolted at its upper end to the rectangular bar R, as shown best in Fig. 3, in which view the die or former is shown at its highest point of stroke and the vertical bar r' resting upon 120 the short lever v'. Now, with the downward movement of the former Q, the bar r', resting upon the lever v', must necessarily force the latter down also, thus raising the arms v, and, by reason of the connecting-levers W, the 125 frames U to their upper limit of movement, as in Fig. 1, and this, too, before the said die or former Q shall have reached the forming-tables N in its downward course, thus fulfilling for the trucks L' the necessary requirement 130 before stated. By this means, also, the said trucks L' are held in their elevated position

until said die or former during its upward stroke shall have passed the said forming-table N.

Suitable slides, n^2 , are secured to the forming-tables N, as shown in Figs. 5 and 10, in such convenient manner as to render them capable of adjustment thereon relative to the required length of a box, for the purpose of bending over the ends of the bottom and sides 10 of the same a half-inch, (more or less,) as shown in perspective view, Fig. 32, of that portion of a box upon which the ends may be pasted. In Fig. 10 the die or former making its downward stroke is shown to have reached 15 a point just below the top surface of the forming-tables N a sufficient distance to have started the formation of the sides of a box, which are shown bent upward on about a forty-five-degree angle. The ends of the bottom and sides of said box have also been partially bent over by contact with the slides n^2 . As the die or former continues to move downward the bent ends, previously referred to, of the bottom and sides of the box are coated with 20 paste by paste-rolls X, said rolls being located directly underneath the forming-tables N, one at either end of the die, and mounted in suitable paste-boxes X', their frames α extending far enough at either end to rest and 25 slide upon the parts α' of the machine-frame. One side and top of the paste-boxes X' are cut away, and the paste-rolls X so mounted therein as that while they are partially submerged in the paste their cylindrical surface will project 30 slightly beyond the side of the paste box, as clearly shown in Fig. 12 of the drawings. Thus when said paste-boxes are moved to their operative position the paste-roll only comes in contact with the card-board box being 35 formed. In order to bring said paste-rolls in contact with the box being formed only when said box is moving downward past said rolls, right-angled levers 1 are provided, which are fulcrumed at 2 to the uprights A A', as shown 40 best in Fig. 11, their short ends pivoted to suitable extension-rods, 3, by which the paste-boxes X' may be adjusted relative to the required length of a box, the opposite ends of 45 said extension-levers 3 being pivoted, at a convenient point to the frames α of the paste-boxes, the longer end of said right angled levers 1 fitting slots formed in and near the top of vertical bars 4, having near their bottom suitable means for preventing any lateral movement 50 of the same, as at 5, Fig. 11, and provided at their lower end with rolls 6, bearing upon cams 7, said cams being mounted upon the counter-shaft G just inside either of the uprights A A'. One of the journals of either 55 paste-roll X projects a trifle beyond the paste-box. Upon these are mounted chain-pulleys 8, which are driven by a suitable chain, 9, passing under one and over the other of said pulleys, (so that they may be rotated in opposite directions,) and thence over pulleys 60 10, conveniently attached to either of the

parts α of the frame, and under a similar pulley, 11, mounted on driving-shaft K.

The card-board forming the ends of a box, after being cut the required size, is deposited 70 in receptacles 12, consisting of plates 13, having vertical walls 14 15, and adjustable wall 16, a tongue, 17, being formed at the bottom fitting groove 18, running longitudinally in the top surface of the table 19, upon which said 75 plates 13 rest, and to which they are secured and rendered adjustable relative to the length of a given box by the screws 20, passing through the same and threaded to nuts 21, fitting slots 22, formed longitudinally in the said table 19. 80

In order to adjust the vertical walls 14 14 relative to a box of given width, against one side of which the said walls 14 must be brought in contact, the table 19 is adjustably mounted upon the bed-frame 23 by means of grooves 24, 85 adapted to receive tongues 25, formed upon top of said bed-frame 23. The said table 19 is rendered capable of being fastened wherever required by a suitable screw, which may pass through slot 26, running transversely in 90 said table, and be threaded to the bed-frame at 27.

The mechanism by which the pieces of card-board forming the ends of a box are delivered from their receptacles 12 consists of the slides 95 28, having dovetailed tongues 29, fitting corresponding grooves, 30, formed in one side of the walls 15, as seen best in Figs. 17, 22, and 23, and having arms 31, the outer ends of which are mounted upon rods 32, rigidly secured to 100 suitable stands, 33, mounted upon one end of the adjustable slide 34, which moves in suitable ways, 35, formed upon the under side of the bed-frame 23, as in Fig. 15 of the drawings, said rods 32 being sufficiently long to 105 admit of proper adjustment of the slides 28 relative to a box of given length by aid of the set-screws 36. The slides 28 occupy openings left for the purpose between adjustable walls 16 and rigid walls 15 and a portion or section 110 of the walls 14 and 15, as clearly seen in Figs. 17 and 18. That part of the slides 28 which carries the card-board out of the receptacles for a distance of slightly more than the length of the said card-board is rabbeted on the side 115 opposite to the tongues 29 to a depth of from one thirty-second to one-sixteenth of an inch, (more or less,) thus forming a shoulder, 23, as seen in Fig. 23, against and by means of which a piece of card-board may rest and be borne 120 toward and to its destination, as also seen in Fig. 23; or these slides may readily be made adjustable relative to the required length of the card-board ends for a given box by making said rabbet of greater length and inserting an adjustable plate of steel, 38, which may form the shoulder 23, the latter method being the most preferable. 125

In practice I find that the forward and return motion of the delivery-slides 28 is best 130 made while the counter-shaft G is making one quarter-revolution; hence the slotted arms 39,

(see Figs. 10, 15, and 28,) having secured within said slots 40 suitable connections; 41, which enter slots 42, formed in the adjustable slides 34, and by which said slides 34 are given a reciprocal motion with the rotative motion of said arms, are mounted upon top of vertical shaft 43, carried in bearings 44 45, as seen in Fig. 2, the lower end of said shaft being provided with the bevel-pinion 46, meshing with the bevel-gear segments 47, constructed as shown in detail, Fig. 27, their pitch diameters being four to one, or one to four, respectively—i. e., the larger gears 47 having just teeth enough to cause the pinion 46 to make one complete revolution, and this while the said gear 47 is making but one quarter-revolution. By this arrangement the slides 28, after the gear 47 has been properly set on the counter-shaft G, are enabled to deliver the card-board ends of a box to their proper position, and return to position shown in Fig. 2 before the forming-die Q, carrying the bottom and sides of a box, shall have reached in its downward course but little beyond the paste-rolls X, thus avoiding contact with the said delivery-slides, which would otherwise occur. To insure the perfect operation of these delivery-slides, provision must be made whereby a certain amount of pressure is continuously applied to the card-board pieces contained in the receptacles 12. This may be accomplished in various ways, one of these being shown in Figs. 22 and 23, in which a follower, 48, is placed in either of the said receptacles, having an arm, 49, provided with a slot, 50, running lengthwise therewith, said arms extending beyond the open end of said receptacles and having connected to their outer ends a cord, 51, passing over grooved wheels 52, and thence downward through slot 50 of said arm 49, where they may be attached to suitable weights of proper power to supply the required pressure to the said follower-plates 48. Said wheels 52 are mounted upon rods 53, supported in bearings 54, secured to the said receptacles 12. To avoid any inaccuracy in depositing these card-board pieces contained in said receptacles, they are carried slightly beyond their proper position by the delivery-slides 28 and against the stop-plate 55, which is hinged, as seen in Fig. 16, to one of the forming-tables N, in such a position as that it may hang a little off or away from the forming-die, except during the time the paste-rolls are distributing paste, as previously described, when, by reason of the connecting-rod 56, slide-bar 57 and a protuberance, 58, formed upon or attached to the vertical actuating-bar 4, said stop-plate 55 is forced with the last of the upward and the first part of the downward motion of said bar 4 into a vertical position, and thus places said card-board pieces so that their ends come exactly flush with the sides of the box, which by this time has reached the bed-table, to be hereinafter described. These card-board pieces are then pressed against those parts of the bottom and sides of the box which have received

a layer of paste, as previously stated, by follower-plates 59, operated by the levers 60, fulcrumed at 61 to the uprights A A', their lower ends being connected by means of a forked link, 62, to a bar, 63, having in its opposite end a suitable stud, 64, which may enter a cam-groove, 65, formed for this purpose in the side of one of the wheels 66, both wheels 66 being mounted side by side upon the counter-shaft G, as seen in Figs. 2 and 26, each operating one of the levers 60. The bars 63 are carried in bearings 67, having caps 68, as shown, and rigidly fastened between parts a³ 80 of the frame, which are connected at either end to the parts a⁴.

The follower-plates 59 may be connected to the levers 60, with a view to the necessary adjustment required relative to the length of a given box, in a simple manner, as seen in detail, Fig. 24. To the outside of the said follower-plates is hinged one end of a rod, to which is threaded a collar and two check-nuts, one at either end of said collar, said collar being connected to the upper end of said lever 60, as shown.

The levers 60 are composed of a frame-work, which affords the opening 69, as seen in Fig. 2, the object of which is to provide a passage 95 for a wide belt, upon which the boxes as completed may be carried away from the machine. This is rendered possible by the movement of the bed-table 70, which is carried upon ways 25, formed upon the bed-frame 23, and is provided with a slot, 71, running transversely therein. A suitable arm, 72, of the same construction as the arm 39, being likewise slotted and connected at 73 to the slot 71 in said bed-table, is mounted upon the vertical shaft 74, 100 carried in bearings 75 76, and provided at its lower end with a bevel-pinion, 77, meshing with a bevel-gear segment, 78, mounted upon the counter-shaft G. In this manner a reciprocal motion is communicated to the said bed-table 70, and its forward and return movement is made while the counter-shaft G is making one quarter-revolution in the same manner as does the slide 34, the pinion 77 and gear-wheel 78 being made from the same pattern from which the pinion and gear 46 47 are made. The moment the pressure-plates 59 shall have pressed the heads onto the box they are both simultaneously removed, the stop-plate 55 also eased off, as seen in Fig. 10, and the bed-table 70 removed from under the forming-die Q, the completed box thereupon dropping through the bed-frame 23 between the slideways 25 and upon a carrier-belt, as previously stated, or other suitable means for removing the said boxes from said machine.

The sliding nuts M' are provided for the adjustable guide-stops M, the slots in said parts M fitting the rectangular part m of the nuts. A thumb-nut, m', being threaded to the stud 130 m², which, by aid of the flange m³, projecting from said nut on the under side of the slot n³ formed in the forming-tables N, said guide-stop M is held in any position desired.

Having thus described my invention, what I claim as new, and desire to secure by Letters Patent, is—

1. The combination, with a receptacle adapted to contain the pieces of card-board composing the bottom and sides of a box, and means, substantially as described, whereby said card-board is delivered, as required, of adjustable forming-tables, feed-rolls, feeding-trucks, and guide-stops adjustably secured to said forming-tables, against which said card-board pieces are carried by said feeding-trucks, and an adjustable die or former for pressing said card-board downward and between said forming-tables, whereby the bottom and sides of a box are formed, all operating as and in the manner set forth.

2. The combination, with a receptacle adapted to contain the pieces of card-board composing the bottom and sides of a box, and means, substantially as described, whereby said card-board is delivered, as required, of suitable forming-tables, feed-rolls, feeding-trucks, and guide-stops adjustably secured to said forming-tables against which said card-board pieces are carried by said feeding-trucks, an adjustable die or former for pressing said card-board downward and between said forming-tables, whereby the bottom and sides of a box are made, and adjustable slides attached to said forming-tables, whereby the ends of said bottom and sides of a box are bent at right angles inward, all operating in the manner and for the purpose set forth.

3. In a machine for making paper boxes, constructed substantially as described, the herein-described paste-boxes, and distributing-rolls mounted therein, so as to be partially submerged in the paste therein contained, one journal of either of said rolls having a suitable chain-pulley mounted thereon, a chain connecting said pulleys with a similar pulley mounted upon the driving-shaft in such manner as to rotate said paste-rolls in opposite directions, and a system of levers and cams connecting said paste-boxes with a counter-shaft, whereby said paste-boxes are simultaneously moved toward the ends of the box at the proper time to distribute a layer of paste thereon, as specified.

4. An adjustable die or former comprising a hub in two sections, one above the other, adjustable slides adapted to enter slots formed in the contacting surfaces of the said hub-sections, and right-angle vertical plates swiveled to the outer ends of said slides, the latter being capable of adjustment to and away from said hub-sections, and said hub sections being adapted to rotate for the purpose of adjusting said right-angled corner-plates relative, respectively, to the length and width of a given box, and means, substantially as described, whereby said hub-sections are held firmly together and said slides in any desired position, all constructed and operating substantially as and for the purpose set forth.

5. The combination, in a machine for making paper boxes, of feed-rolls mounted as shown, for carrying the card-board composing the bottom and sides of a box, spur-gears connecting the same, and a system of bevel-gearing and shafts connecting with the driving-shaft by which said rolls are driven, with the feeding-trucks, the shafts upon which they are carried, the adjustable forming-tables, upon the under side of which one end of either of said shafts is mounted, belt-pulleys and belts connecting the outer ends of either shaft carrying said feeding-trucks with one of the feed-rolls, an adjustable forming-die, a piston-rod to which it is attached, and the mechanism, substantially as shown, by which it is operated, the pressure-trucks carried upon shafts capable of horizontal adjustment in the lower end of vertical sliding frames upon which said shafts are mounted, and mechanism, substantially as shown, operated by said piston-rod, whereby said pressure-trucks are moved vertically to and away from said feeding-trucks during the time said forming-die is making a portion of its up-and-down stroke above said forming-tables, all operating substantially as and for the purpose described.

6. In a machine constructed and operating substantially as shown, the herein-described receptacles adapted to contain those pieces of card-board forming the ends of a box, having one of their side walls adjustable, and means, substantially as described, whereby said receptacles are adjusted relative to the length and width of a given box to be formed by said machine, delivery-slides by which said card-board pieces are carried singly to position, a follower-plate adapted to press said card-board continually against said delivery-slides, mechanism, substantially as described, for giving a horizontal reciprocal motion to said slides, and a bevel-pinion, by which said mechanism is operated, meshing with a bevel-gear segment mounted upon a counter-shaft, and so provided with teeth as that said pinion shall make one entire revolution during one quarter-revolution of said gear-segment, and be at rest during the remaining three quarter-revolutions of said gear-segment, as and for the purpose set forth.

7. In a machine constructed substantially as shown, a bed-table adapted to move horizontally upon a portion of the frame of said machine, and under the forming-die—i. e., in one position affording a seat for the said forming-die when completing the formation of a box, and in another position leaving an opening through which said completed box may drop—and mechanism connecting with a counter-shaft by which said table is moved once in either direction during one quarter-revolution of said counter-shaft, and permitted to remain at rest during the remaining three quarter-revolutions of said counter-shaft, as and for the purpose specified.

8. The combination, in a machine construct-

ed substantially as described, of pressure-
plates located at either end of the forming-die
and adapted to move simultaneously toward
and away from the same, for the purpose, re-
spectively, of uniting the ends with the bottom
and sides of a box, and leaving said box free
to drop from said forming-die when completed,
and mechanism, consisting of levers connect-

ing with cams, mounted upon a counter-shaft,
whereby said pressure-plates are operated. to

In testimony whereof I affix my signature in
presence of two witnesses.

WALTER S. DAVIS.
